DESIGN FOR A COOKY

O'Cal Hanson, Chicago, Ill., assignor to Burry Biscuit Corporation, Chicago, Ill., a corporation of Delaware

Application January 28, 1935, Serial No. 55,097

Term of patent 3½ years

To all whom it may concern:

Be it known that I, O'Cal Hanson, a citizen of the United States, residing at Chicago, in the county of Cook and State of Illinois, have invented a new, original, and ornamental Design for Cookies, of which the following is a specification, reference being had to the accompanying drawing, forming part thereof, wherein Figure 1 is a plan view, and Figure 2 is a view in elevation of a cooky, showing my new design.

I claim:

The ornamental design for a cooky, as shown.

O'CAL HANSON.
